UNITED STATES PATENT OFFICE

WILLIAM H. JAXHEIMER, OF PHILADELPHIA, PENNSYLVANIA, ASSIGNOR TO SMITH,
DRUM & COMPANY, OF PHILADELPHIA, PENNSYLVANIA, A CORPORATION OF PENN-
SYLVANIA

DOOR-LOCKING MECHANISM FOR WASHING-MACHINE CYLINDERS

Application filed July 30, 1927. Serial No. 209,619.

My invention relates to washing machine cylinders having sliding doors and particularly to the means for locking the doors in closed position and for opening and closing the doors. The object of my invention is to provide locking mechanism, the handle lever for unlocking which will be so disposed that the thrust upon it by the operator's hand will not only release the bolts but will also tend to open the door. Other objects which I have in view are to provide the locking mechanism of such character that it can be assembled or disassembled when detached from the door but cannot be disassembled when attached. Other features of my invention will be best understood when described in connection with the drawings which illustrate a washing machine provided with my improvement and in which

20 Figure 1 is a front view of the washing machine cylinder with the doors closed, the casing enclosing the cylinder being shown in section.

Figure 2 is a sectional elevation on the line 25 2—2 of Fig. 1.

Figure 3 is a view similar to Fig. 2, but showing the door open.

Figure 5 is a side elevation of the locking mechanism, the front edge of the door pocket being cut away, and

Figure 6 is an elevation of the locking mechanism viewed from the right of Fig. 5.

A is the casing in which the washing ma-

chine cylinder is located; A¹, indicating a sliding door for the casing, operative over

40 the opening therein indicated at a , a . B is the washing machine cylinder having an opening therein indicated at b , b^1 , the edges of the cylinder plates at b^1 being bent upward in a hook form, as clearly shown in Fig. 2.

45 A guideway for the door, indicated at b^2 , is formed along the side edges of the opening in the cylinder between plates indicated at B^2 .

and a casting C, in which are formed bolt receiving holes, indicated at C¹ and C². D indicates the sliding door, the upper edge of which, D¹, is given a hook form so as to en-

gage with the hook b^1 when the door is closed. The front edge of the door is formed into a depressed pocket, as indicated at D^2 . This pocket ends in a lip D^3 , which fits against the edge b of the cylinder opening.

Referring to the locking mechanism shown on a larger scale in Figs. 4, 5, and 6, F is the lock supporting frame which is intended to fit in the pocket D², as shown, and to be secured therein by rivets. This frame is formed with bearings F¹, F², for a sliding bolt, the outer bearing F² being cast with an end plate F³, from which extends a lip F⁴ which lies in alignment with the side edge of the door and is adapted to fit in the guide-way b². F⁵ is a stop for the handle lever which actuates the bolt; F⁶ is a slot formed in the bottom of the frame F to permit of the assembly and disassembly of the stop finger K. G is a pivot pin extending up from the bottom of the frame F. I is a spring held in the bolt bearing F¹ and fitted against the end of the bolt; I¹, a cap screwing into the bearing F and holding the spring in position. J is a hub fitting on the pivot pin G, from which extends a lever arm J¹, lying below the bolt and having an upwardly extending pin indicated at J². Also extending from the hub J is the handle lever J³ which, by my construction, extends toward the side edge of the door 80

tion, extends toward the side edge of the door or, generally speaking, parallel to the line of the bolt. This handle lever has a beaded top indicated at J^4 , terminating in a downwardly extending end indicated at J^5 . K is a stop finger pivoted on a horizontal pin L, secured to the frame of the lock mechanism and having a heel extension K^1 , from which extends a pin K^2 , entering a slot H^3 in the bolt H. This bolt H is longitudinally movable in the bearings F^1 , F^2 and has preferably a tapered locking end H^1 and is formed with a slot H^2 to receive the pin J^2 and a slot H^3 to receive the pin K^2 .

When it is desired to open the door, the operator grips the handle lever J^3 and draws it toward the bolt, with the result that the pin J^2 is drawn backward, carrying the bolt with it and with the further result that the same effort which withdraws the bolt tends to open the sliding door; the withdrawal of

the bolt acting on the pin K^2 turns the stop finger K upward out of the pocket so that it projects into the path of the sliding door of the casing, as indicated in Fig. 3.

It will be seen that while my locking mechanism can be readily assembled and disassembled when the frame is detached from the door, all its moving parts are undetachable when the frame is secured in position. Detachability of the stop finger K requires that a slot, indicated at F^6 , should be formed in the bottom of the frame, which will permit the stop finger to be turned to a position which will detach the pin K^2 from the slot H^3 when the frame is detached from the door, this slot being closed; when the frame is secured in the pocket the stop finger can not be detached.

Having now described my invention, what I claim as new and desire to secure by Letters Patent, is:

1. A washing machine cylinder having a sliding door, the front end of which is provided with a depressed pocket for the locks and lock actuating mechanism, in combination with a lock supporting frame secured in the pocket having bearings for a sliding bolt and an upwardly extending pivot pin for a bolt actuating lever, a bolt slideable in the bearings of the frame having a slot formed in its under side for a bolt actuating pin, a lever pivoted on the pivot pin to swing laterally in the pocket having an arm extending under the bolt carrying an upwardly extending pin engaged in the slot of the bolt and a handle lever arm extending in the pocket in a direction towards the side edge of the sliding door.

2. A washing machine cylinder having a sliding door, the front end of which is provided with a depressed pocket for the locks and lock actuating mechanism, in combination with a lock supporting frame secured in the pocket having a lip adapted to engage the guideway at the door edge, bearings for a sliding bolt and an upwardly extending pivot pin for a bolt actuating lever, a bolt slideable in the bearings of the frame having a slot formed in its under side for a bolt actuating pin, a lever pivoted on the pivot pin to swing laterally in the pocket having an arm extending under the bolt carrying a pin engaged in the slot of the bolt and a handle lever arm extending in the pocket in a direction towards the side edge of the sliding door.

3. A washing machine cylinder having a sliding door, the front end of which is provided with a depressed pocket for the locks and lock actuating mechanism, in combination with a lock supporting frame secured in the pocket having bearings for a sliding bolt, a horizontally extending pivot pin for a stop finger, a slot formed in its bottom to permit of assembling the stop finger when the

frame is detached from the pocket and an upwardly extending pivot pin for a bolt actuating lever, a bolt slideable in the bearings of the frame having a slot formed in it for a bolt actuating pin, and a second slot formed to receive the actuating pin of the stop finger, a lever pivoted on the pivot pin to swing laterally in the pocket having an arm extending under the bolt, carrying a pin engaged in the slot of the bolt and a handle lever arm extending in the pocket in a direction towards the side edge of the sliding door, and a stop finger pivoted on the horizontal pivot pin having a pin carried on a heel extension and engaged with the bolt slot.
